Specification of Letters Patent.

Patented Nov. 24, 1914.

Application filed January 9, 1914. Serial No. 811,179.

To all whom it may concern:

Be it known that I, CHARLES D. SPEELMAN, a citizen of the United States, residing at St. Joseph, in the county of Buchanan and 5 State of Missouri, have invented certain new and useful Improvements in Lighting-Fixtures; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to lighting fixtures, and more particularly to a connection for the ceiling and hanger pipes in a gas lighting system; the principal object of the invention being to provide means for originally straightening the down sections of the 20 ceiling pipe and retaining same in perpendicular alinement.

It is also an object of the invention to provide a connection of this character for use 25 with combination gas and electric light fixtures, and which may not only serve to straighten and stiffen the down pipes but may also add to the appearance of the fixture.

30 In accomplishing these objects, I have provided improved details of structure, the preferred forms of which are illustrated in the accompanying drawings, wherein:

Figure I is a central vertical section of 35 a connection constructed according to my invention. Fig. II is an elevation of the bell for inclosing the pipe fitting. Fig. III is a perspective view of the stay plate for straightening the down sections of the ceiling pipe.

Referring more in detail to the drawings:—1 designates the down sections of a ceiling pipe which opens through a ceiling 2 in the usual manner and terminates slightly 45 therebelow.

Slidably mounted on the pipe 1 is a disk 3, preferably of suitable metal, and of sufficient diameter to provide an extended bearing against the ceiling, and having an edge 50 flange 4 for contacting the ceiling and spacing the body of the plate therefrom; the bearing hub being extended below the plane of the disk to provide an extended bearing against the down pipe.

55 Threaded onto the down pipe 1 is a reduction fitting 6, having a bell-shaped up-

per portion 7, the edge of which bears against the under face of the disk 3, so that when it is tightened on the down pipe, the edge of the bell presses upwardly against 60 the disk and serves to hold the latter in place.

The body of the fitting is extended downwardly from the upper bell and provided, at its lower end, with a wrench head 10 65 by which it may be tightened on the down pipe and against the stiffening disk, and opening upwardly through the wrench head and body to communication with the down pipe bore, is a bore 11 into which the hanger 70 pipe 11' is threaded, both of the bores being preferably tapered inwardly to provide tapered, threaded connections between the pipes and fitting.

While the connection may comprise merely 75 the disk and fitting, I prefer to use an ordinary canopy 12 for inclosing the first named parts to add to the appearance of the fixture, and also serve to assist in performing the stiffening function of such parts.

In order to adapt the connection for use 80 with combination gas and electrical fixtures, I provide the disk 3 with apertures 13 and the fitting 6 with apertures 14, through which the electric light wires 15 may extend, and with this form of fixture I use the ordinary inclosing tube 16 for containing the electric light wires and mount the canopy 12 on said tube in the usual manner.

While my improvements may be used in 90 connection with any lighting system, it is particularly useful in buildings having high ceilings, wherein the long hanger pipes afford considerable leverage tending to bend the pipes and loosen the connection when 95 the fixtures are handled or swayed, so that leaks are formed in the pipes, the pipes loosened so that they jar and thereby result in damage to gas mantles or electric light filaments, either during their installation or 100 under conditions of use.

By threading the fitting onto the down pipe 1, while the fixture is being installed, any irregularity in the pipe is corrected as the disk is tightened against a flat ceiling 105 through which the down pipe projects, and by tightening the bell against the previously placed disk the correction is not only supplemented, but a perpendicular bearing maintained after the original placement of 110 the parts, on account of the additional leverage attained by extending the point of con-

tact with the pipe downwardly from the point of contact with the ceiling.

In installing the fixture, the ceiling pipes are placed in the usual manner and the disk and fitting applied thereto and tightened against the ceiling to straighten the pipes, and the hanger pipe threaded into the fitting.

When the fixture is adapted for using gas and electricity, electric wires may then be run through the disk and fitting to the lamps, and the portions of the wires extending on the outside of the fitting, as well as the fitting and disk, inclosed by the canopy 11.

It is apparent that the simplicity of the structure not only does not materially increase the cost of the fixture, but also enables the same to be applied without material increase in labor, as all of the parts may be installed by a single workman.

Having thus described my invention, what I claim as new therein, and desire to secure by Letters-Patent, is:—

25 1. In lighting fixtures, a stiffening disk adapted for application to a ceiling pipe and having an edge flange projecting from one of its faces, and a fitting having a threaded aperture for receiving the ceiling pipe and a bell spaced from the aperture of the disk.

20 2. In a lighting fixture, a fitting comprising a bell-shaped upper portion having a boss rising from its base into the bell-shaped

portion, and having threaded sockets extending inwardly through said boss and from the end opposite the boss and meeting to form a conduit.

3. In lighting fixtures, a stiffening disk adapted for mounting on a ceiling pipe, and a bell having a threaded aperture and an annular base flange of less diameter than and adapted for contacting the stiffening member.

4. The combination with ceiling and hanger pipes, of a disk mounted on the ceiling pipe and having an upturned edge flange and down-turned head, and a fitting having a central channel into which the pipes are threaded, and having a bell-shaped upper portion bearing against the under face of the disk adjacent the periphery thereof.

5. The combination with ceiling and hanger pipes having suitable connection, of an apertured disk mounted on the ceiling pipe and having an upturned edge flange and a down-turned head, a fitting having threaded connection with the pipes and bearing against the under face of the disk, wires extended through said apertures, and a canopy inclosing the disk and bell and the lower portions of said wires.

In testimony whereof I affix my signature in presence of two witnesses.

CHARLES D. SPEELMAN.
